[57] CLAIM

The ornamental design for an end plate for flood light housing, as shown and described.

DESCRIPTION

FIG. 1 is a left side front perspective view showing the exterior of the end plate for flood light housing of our new design;

FIG. 2 is a rear elevational view thereof;

FIG. 3 is a right side elevational view thereof showing the interior of the plate;

FIG. 4 is a top plan view thereof;

FIG. 5 is a right side, front perspective view showing the exterior of a modified form of our design, the modified form being reversed for use at the opposite end of the housing.

The interior of the modified form of the end plate is a mirror image of FIG. 3 and the rear is a mirror image of FIG. 2.
